ANTENNA

Seihei Wada, Tokyo, Japan, assignor to Uro Denshi Kogyo Kabushiki Kaisha, also known as Uro Electronics Industries Co., Ltd., Ohta-ku, Tokyo, Japan

Filed Oct. 6, 1972, Ser. No. 295,485

Term of patent 14 years

Int. Cl. D14—03

U.S. Cl. D26—14 F

FIG. 1.

FIG. 2.

FIG. 3.

FIG. 4.

FIG. 5.

FIG. 7.

FIG. 8.

FIG. 1 is a rear elevation view of an antenna embodying my new design with the dipole thereof extended;

FIG. 2 is a side elevation view from the right side of the antenna of FIG. 1 with the dipole thereof extended;

FIG. 3 is a front elevation view of the antenna of FIG. 1 with the dipole thereof extended;

FIG. 4 is a side elevation view from the left side of the antenna of FIG. 1 with the dipole thereof retracted;

FIG. 5 is a side elevation view from the right side of the antenna of FIG. 1 with the dipole extended and the antenna rotated 90 degrees clockwise from the position shown in FIG. 1;

FIG. 6 is a front elevation view from the right side of the antenna of FIG. 5;

FIG. 7 is a rear elevation view from the left side of the antenna of FIG. 5; and

FIG. 8 is a perspective view of the antenna of FIG. 1 with the dipole thereof extended.

I claim:

The ornamental design for an antenna, as shown and described.
